(57) CLAIM

The ornamental design for a beverage cup, as shown and described.

DESCRIPTION

FIG. 1 is a perspective view of a beverage cup in accordance with our new design;

FIG. 2 is a top plan view thereof;

FIG. 3 is a front elevational view, the rear elevational view being a mirror image thereof;

FIG. 4 is a right side elevational view, the left side elevational view being a mirror image thereof; and,
FIG. 5 is a bottom plan view thereof.

The broken line showing further details of the beverage cup are for illustrative purposes only and form no part of the claimed design.
